GERSOLL & BRO., A JOINT-STOCK ASSOCIATION OF NEW YORK.

STEM-WINDING AND STEM-SETTING MECHANISM FOR WATCHES.

1,310,524.

Specification of Letters Patent. Patented July 22, 1919.

Application filed November 13, 1917. Serial No. 201,861.

To all whom it may concern:

Be it known that we, GEORGE F. EBERHARD, WILLIAM T. MALONEY, and FREDERICK W. BOLD, citizens of the United States, and residents of Trenton, N. J., as to Eberhard and Maloney and Thomaston, Connecticut, as to Bold, have invented certain new and useful Improvements in Stem-Winding and Stem-Setting Mechanism for Watches, of which

the following is a specification.

The invention relates to stem winding and stem setting mechanism for watches and it consists in the features and combination of parts hereinafter described and particularly

pointed out in the claims.

In the drawings;

Figure 1 is a plan view of a portion of a watch on the dial side thereof, the dial and hands being omitted.

Fig. 2 is a sectional view along the line 2—2 of Fig. 1 looking from the right.

Fig. 3 is a detail sectional view on line 3—3 of Fig. 1.

Fig. 4 is a sectional view on the line 4—4 of Fig. 1.

Fig. 5 is a plan view of a cover plate and the screws for holding it in place.

Fig. 6 is a sectional view on line 6—6 of Fig. 1.

Fig. 7 is a sectional view similar to Fig. 6 but showing the form of screw and its combination with the spring and cover plate adapted to thin model watches.

In these drawings 1 indicates the dial plate of a watch with the dial removed. 2 indicates the bridge which is attached to the rear side of the dial plate and in a recess in which is located the winding wheel 3. This winding wheel engages a winding gear 4, which is mounted on the winding stem 5, the winding stem being rectangular in cross section and slideable through the winding gear. A sliding clutch 6 is mounted on the winding stem, which is turnable therewith, this clutch having teeth 7 to engage the clutch teeth 8 of the winding gear 4 and also having a set-wheel 9, which is adapted to mesh with intersect wheel 10', in turn meshing with a minute wheel 10, suitably mounted on a stud 11 on the dial plate, this wheel transmitting its motion to the minute hand.

The set-wheel is shiftable with the clutch member and for this purpose a lever 13 has its end engaging a circumferential groove

in the clutch, said lever being pivoted on 55 the pin 14'. This lever is controlled by one arm 15 of a leaf spring and a lever 16 also exerts control on lever 13, the said leaf spring having an arm 15' bearing on the lever 16. The lever 16 is mounted pivotally 60 on pin 17 of the dial plate and it has an arm 18 engaging a groove in the head of the winding stem, shown at 19. The lever 16 also has an arm 20 adapted to work against the edge of the lever 13 and a second arm 65 20' adapted to work against the edge of the tail portion 13', of said lever 13. The parts above described, namely the levers 13, 16, and the spring arms 15, and 15' lie within a recess 22 formed in the dial plate on the 70 dial side thereof and the winding and setting stem together with the winding gear and the clutch 6 with its set-wheel 9 lie within an opening in the bottom of the recess 22. Levers 13 and 16 are simply dropped 75 onto their pivot pins and by placing a cover member 24 in position on a shoulder or seat 23 surrounding the recess 22, the stem winding and setting mechanism will be enclosed in the recess. This cover plate shown 80 in Fig. 5 is mainly of circular form but it has an integral extension 25 and also a supplemental extension 27' with an opening 26 between these extensions so that when the cover plate is placed in position it will act 85 as a bridge over the minute wheel 10 because the extensions 25 and 27' closely overlie the said minute wheel on the dial side face thereof, the opening 26 receiving the small gear arranged coaxially with the 90 minute wheel. The cover plate is held in position by two screws 28 and 29, the said screw 28 having a head overlying the upper or dial side face of the cover plate, said screw also serving as a means for holding 95 the spring composed of the arms 15 and 15', these arms being connected integrally by an eye portion 30 of the spring member, which underlies the head of the screw 28.

The eye 30 of the spring is held in a recess 32 of the dial plate, and the wall of this recess up to the points 31 furnishes a bearing for the eye of the spring, this recess having a contracted mouth between the points 31.

The recess forms an extension of the main recess 22. The arms 15, 15' of the spring member while connected by the eye portion

have independent action on their respective levers *i. e.* the clutch lever 13 and the winding lever 16. The screw 28 is shouldered, the spring eye surrounding the large part 5 thereof, and fitting between it and the wall of the recess. The ends of the spring arms 15, 15' are turned outwardly on curves to reduce friction at the points of contact with the levers 13 and 16. The arms of the spring 10 are bent sharply at the points where they emerge from the contracted mouth of the lateral recess, the effect being that though the two spring arms are connected by the eye portion they act as independent springs 15 and two tensions are possible, one for the clutch lever and the other for the stem lever to meet the different requirements for proper working. The tension of one spring arm is not communicated to and does not disturb 20 the tension of the other spring. The difficulty heretofore experienced by not securing the correct tension on each lever separately is overcome. The spring while having independently tensioned and acting arms is made 25 all in one piece, being thus advantageous to manufacturing.

When the stem 5 is pulled outwardly the lever 16 is turned by its arm 18 engaging therewith and the arm 20 working against 30 the edge of lever 13 will shift the clutch 6 out of engagement with the winding gear 4 and the set-wheel 9 will be set into engagement with the intersect wheel 10' to move the setting train when the stem 5 is turned. 35 Now when the stem is pushed inwardly the lever 16 is moved to the dotted line position shown in Fig. 1, thus removing the arm 20 from the cam-shaped edge of the clutch lever 13 and allowing the spring arm 15 to swing 40 the clutch lever to the dotted line position, thus removing the crown wheel 9 from engagement with the intersect wheel and throwing the clutch 6 into engagement with the winding gear. To insure this action taking 45 place we provide means in addition to the spring and of a positively operating nature, this consisting of the tail portion 13' of the clutch lever 13 and the additional arm 20' on the lever 16, which, when said lever 50 is swung to the left Fig. 1 to remove the arm 20 from engagement with the main part of the clutch lever, will ride against the edge of the tail portion 13' and positively operate the clutch lever, thus avoiding the possibility 55 of the crown wheel sticking in the intersect or other wheel with which it engages. This insures a positive release of the setting mechanism after setting has been done and the stem pushed inwardly, and while the 60 spring 15 aids in this action reliance for safety is had upon the arm 20' and the tail 13' of the clutch lever.

The spring arms will maintain the levers in the position to which they are operated.

65 The cover member holds the levers on

their pins and also retains the spring arms in proper relation to the levers. By removing the cover plate 24, and this can be done from the dial side of the watch access may be had to the parts for repair or removal 70 and this applies to the parts along the stem which are located in the opening at the bottom of the recess 22.

The cover plate 24 has a notch 24' in its edge to receive the shoulder of the holding 75 screw. Suitable peek openings are provided in the bridge plate to observe the operation of various parts.

For thin model watches we use the means shown in Fig. 7 for holding the spring 15 in 80 place, this consisting of a screw 28^x having a conical head, the inclined face of which on one side overlies the edge of the plate 24, said edge being beveled to correspond to the inclined face of the screw head and in this 85 construction the upper face of the screw head is flush with the top surface of the plate 24, this being different from Fig. 6 in which the shouldered screw overlies the said plate 24 and partly above said plate. The 90 construction of Fig. 7 is adapted to thin model watches and the construction of Fig. 6 is adapted for a lower-priced watch of the thicker model. The inclined face of the screw head 28^x bears upon the spring at the 95 eye thereof and assists in holding it in place.

What we claim is:

1. In combination in a watch, a winding lever, a clutch lever, a dial plate having a recess, in which said levers are pivoted, said 100 recess having a lateral extension, a one piece spring having two arms and having an eye fitted in the lateral extension of the recess and with its arms bearing upon the two levers, a cover plate, and a screw for holding 105 the cover plate in place, said screw passing through the eye of the spring and bearing on the inner side of said eye to hold it against the wall of the lateral recess, said lateral recess having a contracted mouth 110 communicating with the main recess, said spring arm being bent sharply at the point where they emerge from the lateral recess, substantially as described.

2. In combination with a winding and setting means with its winding gear, clutch and crown wheel for setting, a two armed lever pivotally mounted and engaging with the winding stem near its outer end to be operated by the longitudinal movement thereof 115 positively in both directions, a clutch lever, the first mentioned lever having one of its arms working against the clutch lever on one side of its pivot and its second arm working against the tail end of the clutch 120 lever to insure release of the crown wheel when the stem is moved from setting position and spring means acting in the two levers, substantially as described.

3. In combination a dial plate having a 130

- recess on its dial side, a winding lever and a clutch lever pivotally mounted in said recess, a spring having an eye portion and arms to engage the said levers, said recess having a 5 lateral extension receiving the eye of the spring, a cover plate for the recess and a screw overlying a portion of the said plate and having a portion bearing on the eye of the spring, said screw having a beveled head 10 and the cover plate having its edge beveled to correspond with that of the side of the screw head, the upper face of the screw head being flush with the cover plate and dial plate, and its inclined side bearing on the 15 spring and holding it against the wall of the recess extension, substantially as described.
4. In combination in a watch, a stem, a grooved head thereon, a winding lever pivotally mounted and having an arm engaging 20 said grooved head to be operated in both directions positively, a winding clutch and crown wheel, slid able on the stem, a clutch lever pivotally supported, and having a tail on the opposite side of its pivot from its 25 clutch engaging arm, the said winding lever having two arms, one of which is on one side of the pivot of the clutch lever, to engage the edge of the tail thereof and the other on the opposite side of the said pivot to engage the 30 edge of the clutch engaging arms, both arms of the winding lever and the clutch engaging arm and tail of the clutch lever being non-resilient, substantially as described.
5. In combination in a watch, a stem, a grooved head thereon, a winding lever pivotally mounted and having an arm engaging 35 said grooved head to be operated in both directions positively, a winding clutch and crown wheel, slid able on the stem, a clutch lever pivotally supported, and having a tail 40 on the opposite side of its pivot from its clutch engaging arm, the said winding lever having two arms, one of which is on one side of the pivot of the clutch lever, to engage the edge of the tail thereof and the other on 45 the opposite side of the said pivot to engage the edge of the clutch engaging arms, both arms of the winding lever and the clutch engaging arm and tail of the clutch lever being non-resilient, and a spring having two arms, 50 one of which engages the winding lever and the other of which engages the clutch lever.

In testimony whereof, we affix our signatures.

GEORGE F. EBERHARD.
WILLIAM T. MALONEY.
FREDERICK W. BOLD.
